UNITED STATES PATENT OFFICE.

FREDERICK H. PRETZ, OF BROOKLYN, NEW YORK, ASSIGNOR TO GEORGE W. SHIEBLER AND COMPANY, OF NEW YORK, N. Y., A FIRM.

DESIGN FOR A HANDLE FOR SPOONS OR FORKS.

SPECIFICATION forming part of Design No. 35,904, dated May 13, 1902.

Application filed April 4, 1902. Serial No. 101,392. Term of patent 3½ years.

To all whom it may concern:

Be it known that I, FREDERICK H. PRETZ, a citizen of the United States, residing at the borough of Brooklyn, in the county of Kings, 5 city and State of New York, have invented and produced a new and original Design for the Handles of Spoons and Forks, of which the following is a specification, reference being had to the accompanying drawings, forming part thereof, in which—

Figure 1 is an elevation of the obverse side of the handle, and Fig. 2 an elevation of the reverse side of the handle.

As shown in the drawings, the handle is of 15 tapering form; and the leading or material features of my design consist of the tortuous, curved, or wave-like edges and the floral decorations on the surfaces, predominating on the obverse side.

20 The design of the obverse side consists of the tortuous, curved, or wave-like edges *a b*,

the floral decorations, comprising a flower *c* at the broad end of the handle, the leaflet ornaments *2, 3, and 4*, and the plain surfaces *e e'*. 25

The design of the reverse side of the handle comprises the tortuous, curved, or wave-like edges *a b*, the leaflet ornament *d* at the broad end of the handle, the leaflet ornament *5*, and the plain surfaces *e' e'*. 30

Upon both the obverse and reverse sides of the handle and generally conforming to the tortuous, curved, wave-like edges are curved forms indicating stem configurations.

What I claim as new, and desire to secure 35 by Letters Patent, is—

The design for the handle of a spoon or fork, substantially as shown and described.

FREDK. H. PRETZ.
